DESIGN FOR A BILLFOLD

John P. Wege, West Bend, Wis., assignor to Amity Leather Products Co., West Bend, Wis.,
a corporation of Wisconsin

Application March 1, 1939, Serial No. 83,270

Term of patent 7 years

To all whom it may concern:

Be it known that I, John P. Wege, a citizen of the United States, residing at West Bend, in the county of Washington and State of Wisconsin, have invented a new, original, and ornamental Design for a Billfold, of which the following is a specification, reference being had to the accompanying drawing, forming a part thereof, and in which:

The back of the billfold is not shown, as the same is substantially plain.

I claim:

The ornamental design for a billfold, as shown and described.

JOHN P. WEGE.
